United States Patent Office

Des. 197,120
Patented Dec. 17, 1963

197,120

BUILDING

Charles W. Battershell, 14828 Gaskill Drive NE,
Alliance, Ohio

Filed July 12, 1963, Ser. No. 75,768

Term of patent 14 years

(Cl. D13—1)

FIG. 1.

FIG. 2.

FIG. 3.

FIG. 2.

The dominant features of my design reside in the portions shown in full lines.

I claim:

The ornamental design for a building, as shown and described.
